UNITED STATES PATENT OFFICE.

ERWIN G. MOYER, OF CHALFON, PENNSYLVANIA.

MAIL-CATCHER.

1,251,267.

Specification of Letters Patent. Patented Dec. 25, 1917.

Application filed January 27, 1916. Serial No. 74,663.

To all whom it may concern:

Be it known that I, ERWIN G. MOYER, a citizen of the United States, residing at Chalfont, in the county of Bucks and State 5 of Pennsylvania, have invented certain new and useful Improvements in Mail-Catchers, of which the following is a specification.

This invention relates to improvements in mail handling apparatus.

10 The principal object of the invention is to provide novel and efficient means for delivering and receiving mail pouches from fast moving trains, so that the liability of the pouches falling under the wheels of the train 15 and being destroyed is effectually prevented.

The invention consists in the provision of means carried by the train for holding the mail pouch in a position to be removed by the receiving means. The receiving means 20 consists in the provision of a member for disengaging the pouch from its supporting means upon the train and a basket to receive the pouch after it has been disengaged from the train by the receiving means. It is an- 25 other object of the invention, therefore, to provide means which will be automatically operable by the mail pouch to cause the delivery of the same from the receiving means to the basket.

30 With the foregoing and other objects in view, the invention consists in the novel features of construction, combination and arrangement of parts, as will be more fully described, illustrated in the accompanying drawings and claimed.

In the drawings:—

Figure 1 is a perspective showing the improved mail delivering and receiving means in use.

40 Fig. 2 is a transverse section on the line 2—2 of Fig. 1.

Referring to the drawings by numerals, wherein is illustrated the preferred embodiment of my invention, 1 designates a portion 45 of a mail car which is provided with the usual door opening 2.

The improved mail supporting and delivering means consists of an arm 3 which is hinged, as at 4, to one side of the door frame 50 so that the same may be readily swung within the car to facilitate placing of the mail pouch upon its outer end, the arm being formed of any suitable material and being

of a length slightly less than the width of the door opening to permit of its swinging 55 within the car, as will be understood.

The arm 3 is provided at its outer end with a hook member 5 which extends downwardly from said arm and is provided with a rearwardly extending lateral projection 6 60 upon which the mail pouch indicated at 7, is adapted to be hung, the pouch being provided with a ring 8 for engagement with the projection 6.

In order to provide means to hold the arm 65 3 in an extended position at substantially right angles to the side of the car a brace member 9 is provided. This brace member is pivoted at its inner end, as at 10 to a bracket carried upon the side of the car 70 above the pivot point 4 of the arm 3, the brace member 9 being mounted within the bracket for vertical swinging movement, as is illustrated most clearly in Fig. 1 of the drawing. This brace member is adapted to 75 be swung downwardly into engagement with the arm 3, when the said arm is swung outwardly with respect to the side of a car, to hold the arm in such extended position, the free end of the brace member 9 being bifurcated to provide tongues for engagement with either side of the arm.

The receiving means consists of a vertical standard 11 which is mounted in any suitable manner to one side of the tracks 85 and is provided near its base with a laterally extending bracket 12 carrying a basket 13, the bracket being extended toward the tracks so that as the mail car passes therewith along with the arm 3 in an extended position the basket will lie directly beneath the end of the arm. At its upper end the standard 11 is provided with a laterally extending rod 14 which is journaled for rotation in a bracket 15 carried by the standard, 90 the inner end of the arm being journaled within the standard, as is shown.

The bracket 15 acts in the nature of a brace for the rod 14, and this bracket is provided with an enlargement 16 having an 100 opening therethrough through which the rod 14 extends. The inner face of this enlargement is recessed, as at 17, throughout substantially one-fourth of its circumference. This recess is adapted to receive a pin 18 carried by the rod 14, the pin being adapted to 105

abut with the walls of the enlargement formed by the recessed portion 17 to limit rotary movement of the rod relative to the bracket.

5 The outer end of the rod 14 is provided with a laterally extending finger 19, the rod 14 being of a length so as to position this finger directly beneath and in vertical alignment with the hook member 5 as the mail 10 car passes the receiving means.

A coil spring 20 is wound about the rod 14 and has one end secured to the rod and the other end secured to the standard 11. This spring exerts a tension to normally hold the rod with the pin 18 in abutting relation with one of the walls of the enlargement 16 so that the laterally extending finger 19 will lie in a horizontal position, as clearly illustrated in Fig. 1 of the drawings.

20 In use, the mail pouch is placed upon the projection 6 of the arm 3 and the arm swung outwardly with respect to the car and locked in such position by means of the brace 9. As the car passes the standard 11 the laterally extending finger 19 of the rod 14 will engage with the ring 8 of the mail pouch and transfer the pouch from the projection 6 to the finger. The spring 20 is of sufficient strength to normally hold the rod 14 in a position so that the finger 19 will lie horizontally. However, the weight of the pouch 7 will overcome the tension of the spring and rotate the arm 14 whereby the finger 19 will be swung downwardly and thus permit of disengagement of the pouch from the finger, the pouch falling into the basket 13, as is obvious.

From the foregoing description taken in connection with the accompanying drawings, it is thought that the construction and operation of the improved mail catcher will be clearly understood, and while I have herein shown and described one specific em-

bodiment of my invention I do not wish to be limited thereto, except for such limitations as the claims may import.

I claim:

1. In a mail bag catcher, the combination with an upright support, of an arm projecting outwardly therefrom in a substantially horizontal direction and adapted to rotate about its own axis, bearings for said arm carried by the support, spring means connected to said arm and tending to rotate the same in one direction, stop means for limiting the rotation of said arm, and means projecting horizontally from the end of the arm to collect a mail sack from a passing train which sack, through its weight, will cause rotation of said arm against the tension of the spring and release the sack from the arm.

2. In a mail catching device, the combination with a fixed vertical standard, and bearings carried by said standard, of a substantially horizontal arm rotatably mounted in said bearings, a pin projecting from one side of said arm to engage stops on one of said bearings and limit the rotation of said arm, a spring surrounding said arm and connected at one end to the standard and at the other end to the arm for normally holding said pin against one of said stops, and a finger projecting from the outer end of said arm in position to engage and collect a mail sack from a passing train, said mail sack through its weight rotating said arm against the tension of the spring to release the sack and permitting said arm to return to its normal position.

In testimony whereof I affix my signature in presence of two witnesses.

ERWIN G. MOYER.
